UNITED STATES PATENT OFFICE

KYLE E. STANT, OF CONNERSVILLE, INDIANA

RADIATOR CAP

Application filed June 30, 1928, Serial No. 289,453. Renewed November 24, 1930.

My invention relates to radiator caps.

It is the object of my invention to provide an easily locked radiator cap that will tightly seal the opening which the cap encloses, and will yieldingly hold the cap in locked position against rattling or unlocking.

It is a further object of my invention to provide mechanism so that, when the cap is in locked position, it will be automatically brought to a proper position for the proper placing of the ornament which the cap may carry.

It is a further object to provide a locking means which will limit the rotating movement of the cap to exactly position it in locked position.

It is an object to provide a rotating locking means and a non-rotative sealing means between the rotating cap and the non-rotating filler spout.

Referring to the drawings:

Figure 1 is a vertical section through the filler spout and radiator cap showing the parts in locked position;

Figure 2 is an enlarged section through the radiator cap showing the exact detail arrangement of the gaskets and flexible diaphragms;

Figure 3 is a section through the radiator cap showing the relative arrangement of the locking lugs and diaphragms;

Figure 4 is a bottom plan view of the radiator cap;

Figure 5 is a detailed side elevation of the filler spout; and

Figure 6 is a top plan view thereof.

Referring to the drawings in detail, 1 is a filler spout which has an outwardly over-turned edge or rim 2 that forms a marginal flange. This rim is turned over to form a locking cam and lug 3. The depending locking cam and lug 3 is approached by a cam rim 4 which guides the locking lug 5 of the cap into engagement with the lug 3 on the filler spout.

These marginal rims 2 are cut away, as at 6, in order to permit of the insertion of the lugs 5 so that the lugs 5 may engage with the cams 4 and be brought into locking engagement with the lugs 3.

The ledges 2 form supporting surfaces for engagement with the gasket 7 that is held between the retaining ring 8 and the flexible diaphragm 9. The flexible diaphragm 9 extends over the top of the gasket 7 while the gasket retaining ring only supports the inner marginal edge of the gasket 7.

Both the gasket retaining ring and the flexible diaphragm have their inner margins yieldingly sealed within the slot 10 of the depending ring 11 of the filler cap 12 by having interposed between one wall of the ring 11 in the slot 10 and the gasket retaining ring and the flexible diaphragm a second gasket ring 13. Thus the joint of the gasket retaining ring and flexible diaphragm with the filler cap is sealed and the joint between the flexible diaphragm at its outer margin and the marginal ledge 2 of the spout 1 are sealed, the latter being sealed by the gasket 7.

As these gaskets are of fiber, the hot water in the radiator will tend to cause them to seal and maintain the parts in increasingly close sealed engagement to prevent unlocking, rattling and leakage.

When it is desired to place the radiator cap on the spout, the three spaced locking lugs 5 are so positioned as to pass through the cut-away area 6 of the spout and then when they are in position to engage the cam surfaces 4 the radiator cap is rotated until the lugs 5 engage with the lugs 3 which serve to exactly position the radiator cap and its ornament.

This locking movement is approximately sixty degrees clockwise. The cams 4 on the spout 1 will compress the diaphragm 9 in the cap 12 thus sealing the opening of the spout 1 against leakage.

It will be understood that in the operation of this device the filler cap rotates relatively to the diaphragm 9 and gasket 7 which remains stationary in engagement with the top of the spout 2 while the cap 12 continues to rotate to the end of its movement. The gasket 13 turns with the cap. The purpose of maintaining the gasket 7 and its associated diaphragm 9 stationary is to permit long life of the gasket 7 where it comes in contact with the top of the filler spout.

It will be understood that I desire to com-

prehend within my invention such modifications as may be necessary to adapt it to varying conditions and uses.

Having thus fully described my invention,
5 what I claim as new and desire to secure by
Letters Patent, is:

1. In a radiator cap, a cover portion, marginal depending locking portions, and an internally disposed diaphragm supporting portion, a flexible diaphragm supported thereby, a gasket retaining ring, a gasket between said diaphragm and said ring.
- 10 2. In a radiator cap, a cover portion, marginal depending locking portions, and an internally disposed diaphragm supporting portion, a flexible diaphragm supported thereby, a gasket retaining ring, a gasket between said diaphragm and said ring, and a second gasket associated with the inner margins of the 15 gasket retaining ring and the flexible diaphragm for sealing said retaining ring and diaphragm to the depending supporting means of the cap.
- 20 3. In combination in a closure mechanism of a filler spout having a marginal, laterally extending rim turned downwardly at intervals to form cams and stop lugs arranged in spaced pairs with cutaway portions in the rim therebetween, a radiator cap having spaced marginal locking lugs carried on the 25 inner periphery thereof adapted to register with the spaces in the filler spout rim between the stop lugs and cams whereby when the lugs are inserted in said cutaway spaces 30 the filler cap may be rotated into locked position, and a yielding sealing means carried by said cap consisting of a flexible diaphragm, a gasket beneath said flexible diaphragm engaging said marginal rim of the filler spout, 35 a gasket retaining ring for retaining said gasket in position, and a second gasket for sealing the connection of the gasket retaining ring and flexible diaphragm to the radiator cap.
- 40 45 45 In testimony whereof, I affix my signature.
KYLE E. STANT.
